UNITED STATES PATENT OFFICE.

FRANK C. ANDERSON, OF CINCINNATI, OHIO.

SWITCH-STAND.

1,360,862.

Specification of Letters Patent. Patented Nov. 30, 1920.

Application filed July 1, 1920. Serial No. 393,355.

To all whom it may concern:

Be it known that I, FRANK C. ANDERSON, a citizen of the United States, residing at Cincinnati, in the county of Hamilton and State of Ohio, have invented certain new and useful Improvements in Switch-Stands, of which the following is a specification.

My invention relates to ground-lever parallel-throw switch-stands. Its object is to add to the range of choice of leverage, in the transmission of the switch-throwing effort from the handle to the switch point-rail, whereby there may be combined ease of manual switch-throwing operation with such control of the point-rails by the weighted handle that yielding and vibration of the latter, under normal traffic, will be negligible, even without the use of a latch, thereby permitting the use of the stand for yard use without latches; but so that the leverage provided will permit excess strain on the point rail, as when the switch is run through, to raise the handle lever and avoid breakage of the stand or rails without resort to resilient or breakable connections. A further object is to provide such an improved switch-stand with a target-shaft, to be operated in accordance with the switch-throwing operation, but which will be relieved of the heavy strain of the switch-throwing operation or the excessive strains imposed on the stand under normal or unusual traffic, in the circumstances just alluded to. A further object is to provide for the ready assembly of the stand, and for its adjustment to different switches, and to compensate for wear in the connections, in accordance with the aforementioned objects; and in general, to make the stand as simple and economical of construction, installation and maintenance as is consistent with the high standard of reliability demanded of equipment of this character. Other objects will appear in the course of the ensuing description.

I attain these objects by the device illustrated, for example, in the accompanying drawing, in which—

Figure 1 is a general perspective view of part of a railway switch equipped with my switch-stand;

Fig. 2 is a perspective detail view of the base;

Fig. 3 is an enlarged sectional plan view of the stand, the section being on a plane corresponding to the line 3—3 of Fig. 4;

Fig. 4 is a sectional front elevation, on the same scale, the section being on a plane corresponding to the line 4—4 of Fig. 3;

Fig. 5 is a vertical front-to-rear section, on the same scale, on a plane corresponding to the line 5—5 of Fig. 3;

Fig. 6 is a vertical lengthwise section of the adjustable crank; and

Fig. 7 is a perspective detail view of one of the shims.

The base of the stand comprises, in an integral casting, preferably of malleable iron, a main generally flat middle part 1 with curved junction parts 2 at opposite ends, extending down to the foot-plates 3, which are generally flat and are adapted to rest on the head-blocks 4 of the switch installation. These plates 3 preferably have the end notches 5 and the openings 6 and 7, 70 suitably distributed across the grain of the wooden head-blocks, through which spikes 8 are driven into the head-blocks, securing the stand rigidly thereon as usual. The foot-plates 3 extend considerably past the front of the main part 1, where each plate 3 has formed on it an upstanding lever-rest 9, elongated across the plate and aligned with each other across the base, with their tops longitudinally channelled, by having 85 side ribs 10 that taper downwardly and inwardly toward each other across the respective rest 9. Opposite the junction of the extended part of each foot-plate 3 with the main rear part thereof that is coextensive with the main base part 1, there is a rather large oblong opening 11 through the plate, leaving this junction of much reduced cross-section. Small ribs 12 extend up from the foot-plates 3 onto the curved junction 90 parts 2.

The base also comprises, integrally formed with the just described parts, a front shaft bearing 13 extending at the middle of the front of the main part 1, with 100 flanking ears having flat surfaces upward, with bolt-holes down through them surrounded by annular alining bosses 15; and a slight raised rim 16 continues from these ears 14 back along the ends of the main part 1 and along the rear edge thereof, widened at the rear corners, with similar bolt-holes having the similar bosses 15 therearound. At the middle of the rear of the main part 1 is a semi-circular extension 105 17 with the rim 16 continued around its edge and with the relatively large vertical

crank-and-clutch bearing opening 18 down through it centrally. Between this opening 18 and the front shaft-bearing 13 is the depression 19, of semicylindrical shape, spaced forward from the opening 18 and coaxial with the shaft-bearing journal depression 20, which enters the front of this depression 19. The main plate 1 is considerably thickened throughout the extent 5 of its rear extension 17 and forward to the rear end of the depression 19, affording ample up-and-down length to the bearing opening 18. Preferably, a heavy rib 21 extends from each side of the depression 19, 10 joining the wall thereof, and continues across the bottom of the main part or plate 1 to the respective curved junction part 2, which it joins; being substantially alined with the rear end of the depression 19 15 (Fig. 5).

The base further comprises, integral with the aforescribed parts, three pedestals; two of these, 22, being at the front, slightly spaced back from the rim 16 and each running 20 across the main plate 1 from near the rim 16 at the end to within the depression 19 at the front end thereof. The third pedestal 23 runs parallel with the front pedestals 22, from near the rim 16 at one 25 end to near the rim 16 at the other end of the plate 1, at the rear end of the depression 19. The front and rear pedestals 22 and 23 are thus considerably spaced apart forwardly and rearwardly, and the front pedestals 22 are considerably spaced apart at 30 their inner ends, equidistant from the front-to-rear center line of the base, along which are alined the front shaft-journal bearing 20 and the rear crank-and-clutch bearing opening 18; and the rear pedestal 23 runs across this center line. 35

The casing is another casting, which may be of gray iron with continuous preferably flat top 24, front 25 which is straight except 40 for the front shaft-bearing 26 and ears 27 having bolt-holes with surrounding sunken parts to fit on the annular alining bosses 15 of the base ears 14, sides 28 and back 29, all conforming to the rim of the base, and having at the rear corners the ledges 30 with the upper casing walls curved in there-around and with bolt-holes having surrounding sunken parts to fit on the rear alining bosses 15 of the base. In this conformity 45 to the base-rim 16 this casing has the substantially semicylindrical rear extension; and the top 24 of this casing has down through it the target-shaft-bearing opening 31 in vertical alinement with the base opening 18 when the casing is alined on the base, to which latter the casing is firmly secured by the bolts 32 through the front ears and the bolts 33 through the rear ledges 30 and rear corner parts of the base. This casing 50 thus has a fully open bottom, permitting

the interior working parts of the stand to be fully assembled on the base; after which the casing may be brought down thereover in a very simple manner and bolted to the base, completing the assembly. 70

The handle-lever 34 has at one end the weight-handle 35 of approved design, and at its other end, preferably forged integrally with the lever 34, the pinion shaft 36. This shaft lies in the front shaft-bearings of the 75 base and casing, and has keyed on it the pinion segment 37 occupying the depression 19 of the base and having at its front end a short hub 38, through which hub is a pin 39, passing through the shaft 36. As shown, 80 this pinion-segment has five teeth, the terminal ones of the series being diametrically opposite; that is, it is an eight-tooth pinion with three of the teeth omitted at one side. It is so keyed to the shaft 36 that its middle 85 tooth is alined with the handle lever 34. The rear pedestal prevents escape of the pinion key.

The rack 40 comprises in one casting, preferably of malleable iron, the flat body 41, 90 the six teeth 42 in longitudinal series along the bottom of the body, and the parallel front-to-rear upstanding jaws 43 considerably spaced apart equidistant from the front-to-rear median line of the body, symmetrically to which the downwardly projecting teeth 42 are also arranged. This rack has its teeth 42 shorter than the front-to-rear width of the body 41, leaving equal longitudinal bearing surfaces 44 and 45 at 95 front and rear, which bear on the tops of the base pedestals 22 and 23, respectively; and the teeth 42 are of such width as to have an easy fit between the front and rear pedestals, whereby the rack is supported for 100 transverse travel. Thus supported, the pedestals 22 and 23 being of the proper height, the rack teeth 42 mesh with the teeth of the pinion-segment 37, symmetrically. Lugs 41', at the corners of the body 41, act 105 as guides.

The target-shaft 46 is suitably designed in its upper part, with the target-elements 47 fixed thereto in approved manner. The lower end of this target-shaft 46 is threaded, 115 and some distance above the threads has a transverse opening. The crank 48 comprises, in one casting, preferably malleable iron, the rather large hub 49 down through which the target shaft 46 fits 120 snugly, and the front head 50, which has an easy fit between the jaws 43 of the rack 40 when the crank is thus mounted on the target-shaft 46 with the latter bearing in the casing top opening 31 and the lower-end part of the hub 49 fitting down in the crank-and-clutch opening 18 of the base. This lower-end part of the hub 49 has its lower face transversely grooved, and up a proper 125 distance has an annular flange 51 that rests 130

on the top of the base main plate 1 around the opening 18, holding the crank 48 at the right height to work easily with the rack 40; while the target-shaft is in turn supported by this crank by a pin 52 slipped through a transverse opening in the hub 49 at the right height and through the target-shaft opening. This pin 52 has a head 53 large enough to extend out against the inner concave wall of the rear casing extension and thus prevent material outward displacement of the pin 52 from the hub and shaft.

The crank-block 54 is of general cylindrical shape with opposite sides flattened, and having a crank-arm opening through it from one flat side to the other; and it has in its upper end a threaded or tapped opening with clutch-teeth 55 at opposite sides. The aforescribed lower-end part of the crank-hub 49 extends only partly through the thickened part of the base main plate 1, in the opening 18; and this upper-end part of the crank-block 54 extends up into the lower part of this opening 18 and its teeth 55 fit in the transverse groove of the lower-end part of the hub 49, while the threaded lower-end part of the target-shaft 46 is screwed down into the tapped opening of the crank-block 54, thus holding the latter up on the crank 48. Any slight looseness of fit of the teeth 55 in the grooves, as is unavoidable with cast formation of these parts, does not impose the switch-throwing and switch-holding strain on the target-shaft 46, because the crank-block 54 can turn on its threads until these teeth engage with the sides of the grooves.

The crank-arm 56 is generally of the shape of a pin or bolt, with one end part 57 threaded and its other end part 58 flattened into the form of an eye; and it also comprises, next to this eye part 58, a flange 59 to bear against the adjacent flat side of the crank-block 54 when inserted through the opening of the latter, and has a bottom arm 60 on the lower end of this flange 59, to extend under the bottom of the crank-block 54 and some distance past the opposite side thereof. A number of shims or washers 61 are provided, each of general U-shape (Fig. 7) but with the members of the U flat transversely, such as would be formed by stamping these parts from relatively heavy sheet metal. These shims 61 are inverted and placed with their flat sides together, straddling the crank-arm 56 between said opposite flat side of the crank-block 54 and the nut 62 screwed onto the threaded end part 57 of the crank-arm 56.

The connecting-rod 63 is forked, with its members 64 straddling the eye part 58 of the crank-arm 56 and receiving the crank-pin 65 down through the members and eye, in a well known manner, in which position the

pin 65, as here exemplified, is held by a cotter 67 through the lower projecting part of the pin 65, which latter has its head down on the top of the upper connecting-rod member 64 and is thus supported. The other end of the rod 63 is forked, with its members 68 straddling the head-rod 69 and connected thereto by a pin; the head rod being suitably connected to the switch point-rails 70, only one of which is shown (Fig. 1). The shims 61 have their lower ends resting upon the top of the extended part of the bottom arm 60. These U-shaped shims or washers 61, inverted, are readily inserted or removed by loosening the nut 62, without taking the crank-arm 56 out of the crank-block 54; and when the nut 62 is tightened, are held firmly in place. The slight turning of the crank-block 54 on its threads on the target-shaft 46 avoids shearing of the pin 52 under heavy strain on the parts, which, if occurring, would permit the crank-block 54 to drop loose from the crank 48.

In assembling the stand, the handle-lever 34 is placed in its bearing 20 in the base, with its pinion-segment 37 keyed and pinned thereon as before described; and the rack element 40 is placed thereover, in mesh with the pinion-segment 37 and midway of its travel when the lever 34 is upright. The target-shaft 46, before its target elements 47 are assembled thereon, is screwed into the upper end of the crank-block 54 and the crank 48 has its hub 49 slipped down on the shaft 46 until its groove receives the teeth 55 of the crank-block 54. Then the opening for the pin 52 is bored in the crank-hub 49 and shaft 46 and the pin 52 is passed through these parts. This assembled mechanism is now placed on the base by passing the crank-block 54 down through the opening 18 and allowing the crank-head 50 to come between the rack-jaws 43. The casing is then placed on the base with the front bearing of the casing over the pinion-shaft 36; and, this casing being bolted to the base as before described, holds all of the inner parts in their proper positions, without further adjustment or fastening.

The crank-block 54, projecting below the rear part 17 of the base, receives the crank-arm 56 and its shims 61 and nut 62 as before described; the arm 56 being inserted from one side or the other, according to the position of the switch to which the stand is applied. It is made longer or shorter in throw by transferring one or more of the shims 61 from one side of the crank-block 54 to the other, in convenient manner as before described. The bearing of the lower ends of the inverted U-shaped shims 61 on the extension of the arm 60 prevents their turning around on the crank-arm 56, which, if permitted, might result in their

working loose. The adjustment thus permitted by transferring the shims 61 allows provision for variation in length of throw, either initially, due to switches built to throw different amounts, or after considerable use of the switch, when the throw of the crank must be increased due to wear of the connecting parts.

Where the stand is used in yards or other places in which it is not liable to be tampered with, it is to be installed without latches; the foot-plate extensions receiving the handle-lever 34 on the rests 9, in the channeled tops thereof, and the weight of the handle 35 and the lever itself being depended upon to prevent excessive vibration of the working parts and consequent excessive opening of the point rails under normal traffic, but to yield upward under abnormal strain, as in running through the switch from the opposite end thereof, under the improved conditions as will later be explained. When the switch is used for main line or other exposed positions, and latches are necessary, to permit locking of the switch, the foot-plate extension may be readily cut away from the main foot-plate parts contiguous to the base main part, by severing, with a chisel, at opposite sides of the openings 11, in the reduced cross-sections caused by these openings. This leaves space on the head-blocks 4 for installing any approved latch of the proper dimensions to receive the handle-lever 34 in the well known manner.

My improved switch-stand is designed to dispense with latches, except where prerequisite to locking the switch, owing to the use of the intermediate lever or crank 48, and the use of a spur pinion-segment 37; as distinguished from the well known bevel pinion-segment working directly against the switch-throwing crank element through a bevel gear-segment. The length of the handle-lever should not be varied materially; and by making the spur pinion-segment relatively small, as is possible whereas a bevel pinion must be of considerable size, as dictated by the requirements in casting its teeth at the small end, I am enabled to provide the required leverage without varying the handle-lever length. Similarly, the switch-throwing crank, as here represented by the crank-arm and block, must be of the length required to properly throw the switch; it cannot have its length varied to adjust the leverage for the purpose here in view. But the intermediate crank 48 can be of such length as may be required for this purpose, to contribute, in conjunction with the properly sized pinion-segment 37, just the proper leverage, or ratio of effort of transmission from track to handle-lever and weight-handle, to subserve the purpose of dispensing with latches.

Once latches are eliminated from the in-

stallation of yard switches and switches used under conditions similar to yard use, where locking is not necessary or permissible, owing to the frequent throwing demanded, the use of breakable connections, as breakable cranks or crank-pins or other parts of proportions for breakage under abnormal strain, and the use of resilient connections, such as springs and the like to yield under the excessive pressure, are also eliminated. The cost of the installation, and also of the upkeep, may thus be greatly reduced; as no breakable parts need be renewed, and any element of uncertainty with spring connections is avoided.

My improved stand is constructed with these purposes in view, yet with all of the precautions against derangement observed in other switch-stands. The target-shaft 46 does not transmit any of the switch-throwing strain; this being taken by the engaged crank 48 and crank-block 54, and the shaft 46 acting only as a means of holding these heavy parts together, in addition to its primary function of turning the target-elements 47, or the target lamp that may be mounted thereon. These effective connections are made by simple means, as is manifest from the description of their assembly; so that the entire construction is of cost not out of proportion to the advantages derived thereby.

It will be understood that the target-shaft may be of any required height, as in other stands; and any of the other parts may have their design or dimensions varied, and be made of such materials or in as many different parts as may be expedient under varying conditions. Therefore, while certain constructional details are deemed preferable in connection with my invention, and I have shown and described these rather specifically in elucidating the construction and use of my invention, as is required, I do not wish to be understood as being limited to such precise showing and description, but having thus fully described my invention, what I claim as new and desire to secure by Letters Patent is:

1. In a switch-stand, mechanism comprising a lever and a spur pinion coaxially connected, a rack above and meshing with said pinion, an intermediate crank operatively engaging with said rack thereabove, a direct switch-throwing crank coaxially connected with said intermediate crank, and means operatively supporting said mechanism.

2. In a switch-stand, mechanism comprising a lever and a spur pinion coaxially connected, a rack above and meshing with said pinion, an intermediate crank operatively engaging with said rack thereabove, a direct switch-throwing crank coaxially connected with said intermediate crank, a base forming bearing and supporting means for said

mechanism and having an opening through which said intermediate crank and said direct switch-throwing crank are connected, and a substantially flat-topped open-bottomed casing fitting on said base over and around said mechanism.

3. In a switch-stand, supporting means, a rack element and a lever operatively mounted on said means, a spur pinion coaxially connected to said lever and meshing with the teeth of said rack, an intermediate crank directly engaging with said rack element and having a bearing in said supporting means, and a direct switch-throwing crank coaxially connected with said intermediate crank and off-set downwardly therefrom.

4. In a switch-stand, supporting means, mechanism operatively supported by said means, comprising a lever and a spur pinion coaxially connected, a rack element having teeth meshing with said pinion, an intermediate crank in direct engagement with said rack element, and a direct switch-throwing crank coaxially connected with said intermediate crank and extending below the lowest part of said supporting means for connection to switch-connecting means therebelow.

5. In a switch-stand, mechanism comprising a lever and a spur pinion coaxially connected, a rack element above said pinion and having teeth on its bottom meshing with said pinion, an intermediate crank operatively engaging directly with said rack element, a direct switch-throwing crank coaxially connected with said intermediate crank, and means operatively supporting said mechanism.

6. In a switch-stand, mechanism comprising a lever and a spur pinion coaxially connected, a rack meshing with said pinion, an intermediate crank operatively engaging with said rack, a direct switch-throwing crank coaxially connected with said intermediate crank, and a base comprising a main part forming bearing and supporting means for said mechanism, with an opening through which said intermediate crank and said direct switch-throwing crank are connected, and comprising downwardly projected foot-plates at opposite ends of said main part, extending past said main part opposite said lever, with lever rests on these extensions of the respective foot-plates, each one of said foot-plates being materially reduced in cross-section in its region where it extends past said main part, whereby it may be readily detached from said main part to leave space for a latch for said lever.

7. In a switch-stand, mechanism comprising a lever and a pinion coaxially connected, a rack meshing with said pinion, an intermediate crank operatively engaging with said rack, a crank block coaxially connected

with said intermediate crank, a crank-arm 65 extended through said crank-block, having one end threaded and having rod-connecting means at its opposite end, a nut on said threaded end, and a shim between said nut and said crank-block.

8. In a switch-stand, mechanism comprising a lever and a pinion coaxially connected, a rack meshing with said pinion, an intermediate crank operatively engaging with said rack, a crank-block coaxially connected 75 with said intermediate crank, a crank-arm extended through said crank-block, having one end threaded and having rod-connecting means at its opposite end, a nut on said threaded end, and a U-shaped shim inverted 80 and astraddle of said crank-arm between said nut and said crank-block.

9. In a switch-stand, a base comprising a front-to-rear shaft-bearing at its front, pedestals extending up at the rear of said bearing and spaced apart at opposite sides of the center line of said bearing, a lever with a shaft in said bearing, a pinion fixed on said shaft to the rear of said bearing, a rack element having downwardly projecting 90 teeth meshing with said pinion and a longitudinal bearing on said pedestals, an intermediate crank mounted on said base on an upright axis, to the rear of said rack element, and operatively engaging with 95 said rack element, and a direct switch-throwing crank coaxially connected with said intermediate crank.

10. In a switch-stand, a base comprising a front-to-rear shaft-bearing at its front, 100 pedestals extending up at the rear of said bearing and spaced apart at opposite sides of the center line of said bearing, a rear pedestal some distance back of said front pedestals, extending across said center line, a 105 lever with a shaft in said bearing, a pinion keyed on said shaft at the rear of said bearing, with its rear end close to said rear pedestal, whereby its key is retained by said rear pedestal, a rack element having downwardly projecting teeth meshing with said pinion, and surfaces at opposite sides of said teeth bearing on said front and rear pedestals, respectively, an intermediate crank mounted on said base on an upright axis, 110 to the rear of said rack element and operatively engaging with said rack element, and a direct switch-throwing crank coaxially connected with said intermediate crank.

11. In a switch-stand, mechanism comprising a lever and a spur pinion coaxially connected, a rack meshing with said pinion, an intermediate crank operatively related to said rack, a direct switch-throwing crank coaxially connected with said intermediate 120 crank, a base forming bearing and supporting means for said mechanism and having an opening through which said cranks are

connected, and a casing over and around said mechanism, with an open bottom fitting on said base in substantially a single plane.

12. In a switch-stand, mechanism comprising a lever and a spur pinion coaxially connected, a rack above said pinion, meshing with said pinion, an intermediate crank operatively engaging with the upper part of said rack, a direct switch-throwing crank 10 coaxially connected with said intermediate crank, a base forming bearing and supporting means for said mechanism and having an opening through which said cranks are connected, and a substantially flat-topped casing over and around said mechanism, with an open bottom fitting on said base in substantially a single plane.

13. In a switch-stand, a base comprising a front - to - rear shaft-bearing at its front, 20 front pedestals extending up at the rear of said bearing and spaced apart at opposite sides of the center line of said bearing, a rear pedestal some distance back of said front pedestals, extending across said center line, a lever with a shaft in said bearing, a spur pinion keyed on said shaft at the rear of said bearing with its rear end close to said rear pedestal, whereby its key is retained by said rear pedestal, a rack element 25 having downwardly projecting teeth meshing with said pinion and surfaces at opposite sides of said teeth forming longitudinal bearings on said front and rear pedestals, respectively, and having upwardly projecting fixed jaws on its upper side, said base having an opening down through it to the rear of said rear pedestal, in front-to-rear alinement with said shaft-bearing, a target-shaft, an intermediate crank having a hub 30 with said target-shaft extending down there-through, a pin through said hub and through said target-shaft, said intermediate crank extending forward and having a head between said jaws of said rack element, and 35 its hub having a flange bearing on said base around said opening of said base, with the lower end part in said opening and having engaging means on the lower end thereof, the lower end part of said target-shaft being threaded, a crank-block screwed onto said threaded lower end part, with engaging means engaging with the engaging means on the lower end of said intermediate crank hub, said crank-block having opposite flat sides with an opening through it from one flat side to the other, a crank-arm 45 extending through said opening in said crank-block, with rod-connecting means at one end and having its opposite end threaded, 50 a nut on said threaded end, a U-shaped shim inverted and astraddle of said crank arm between said nut and the adjacent flat side of the crank-block, and a substantially flat-topped open-bottomed casing fitting down

on said base over and around said mechanism, with its wall engaging said pin to hold it in said intermediate-crank hub and target-shaft, said target-shaft extending through and bearing in the top of said casing, and said base having, at opposite ends, 70 outside said casing, downwardly projected foot-plates with means to secure the switch-stand in working position, each foot-plate extending forwardly past the front of said casing, with a respective lever-rest thereon 75 in position to receive said lever, and having, near the beginning of its forward extension, a reduced cross-section, whereby the forwardly extended part may be readily detached from the rear part, to leave space for 80 a latch for said lever.

14. In a switch-stand, mechanism comprising a lever and a pinion coaxially connected, a rack in mesh with said pinion, an intermediate crank in engagement with said 85 rack, a casing around said intermediate crank, a target-shaft extending coaxially through said crank, a pin non-rotatively fixing said target-shaft in said crank and held in its fixing position by said casing, and 90 a direct switch-throwing crank held in operative connection with said intermediate crank by said target-shaft.

15. In a switch-stand, mechanism comprising a lever and a pinion coaxially connected, 95 a rack in mesh with said pinion, an intermediate crank in engagement with said rack, a direct switch-throwing crank, the two cranks having mutually engaging means for operative connection, and a shaft screwed 100 into said direct-switch-throwing crank and non-rotatively fixed in said intermediate crank.

16. In a switch-stand, a base comprising a front-to-rear shaft bearing at its front, 105 and pedestals extending up at the rear of said bearing and spaced apart at opposite sides of the center line of said bearing.

17. In a switch-stand, a base comprising a front-to-rear shaft bearing at its front, 110 pedestals extending up at the rear of said bearing and spaced apart at opposite sides of the center line of said bearing, and a pedestal to the rear of said spaced-apart pedestals, extending across said center line.

18. In a switch-stand, a base comprising a front-to-rear shaft-bearing at its front, 115 and pedestals extending up at the rear of said bearing and spaced apart at opposite sides of the center line of said bearing, and having an opening down through it back of said pedestals, in front-to-rear alinement with said shaft-bearing.

19. In a switch-stand, a base comprising a front-to-rear shaft bearing at its front, 120 pedestals extending up at the rear of said bearing and spaced apart at opposite sides of the center line of said bearing, and a

pedestal to the rear of said spaced-apart pedestals, extending across said center line, said base having an opening down through it back of said pedestal, in front-to-rear 5 alinement with said shaft-bearing.

20. In a switch-stand, a rack element comprising a main flat part with teeth and a longitudinal bearing surface along on one flat side, and fixed crank-engaging means 10 projecting from its opposite flat side, adapted to admit a crank moved toward said side at right angles to the flat surface of said side.

21. In a switch-stand, a rack element comprising a main flat part with teeth and a longitudinal bearing surface along on one flat side, and fixed longitudinally spaced jaws projecting from its opposite flat side.

22. In a switch-stand, a base having an opening down through it, and a crank having a hub extending down into said opening with a flange bearing on said base around said opening, and having engaging means on its lower end part.

25. 23. In a switch-stand, a crank-block of general cylindrical shape with opposite flat sides with an opening through it from one flat side to the other, and having engaging means on one end and an axial threaded 30 opening in said end.

24. In a switch-stand, a crank-block of general cylindrical shape with opposite flat sides with an opening through it from one flat side to the other, a crank-arm through 35 said opening with rod-connecting means at one end and threaded on its opposite end part, a nut on said threaded part, and a shim of general U-shape between said nut and said crank-block, astraddle of said 40 crank-arm.

25. In a switch-stand, a shim of general U-shape.

26. In a switch-stand, a shim of general U-shape, with the members of the U flat, as would be formed by cutting from a flat 45 sheet.

27. In a switch-stand, a crank-block with a transverse opening, a crank-arm through said opening with rod-connecting means at one end and having retaining means at its 50 opposite end part, and a shim astraddle of said crank-arm between said crank-block and said retaining means, with one side open whereby it may be slipped onto and off of said crank arm sidewise of the crank-arm. 55

28. In a switch-stand, a crank-block with a transverse opening, a crank-arm through said opening with rod-connecting means at one end and having retaining means at its opposite end part, and having a part extending from under said crank-block toward said retaining means, and a shim astraddle of said crank-arm between said crank-block and said retaining means, with one side open whereby it may be slipped down 60 onto the crank-arm or up off of the crank-arm, and bearing against said extending part whereby it is prevented from turning 65 around on said crank-arm.

29. In a switch-stand, a crank-block with 70 a transverse opening, a crank-arm through said opening with rod-connecting means at one end and having retaining means at its opposite end part, and having a part extending past said crank-block toward said 75 retaining means, and a shim astraddle of said crank-arm between said crank-block and said retaining means, with one side open whereby it may be slipped onto and off of said crank-arm sidewise of the crank-arm, 80 said extending part preventing turning of said shim on said crank-arm.

FRANK C. ANDERSON.
